UNITED STATES PATENT OFFICE

115,514

DESIGN FOR A GLASS TEAKETTLE

John G. Francis, Chicago, Ill., assignor to Chamberlain, Inc., Chicago, Ill., a corporation of Illinois

Application November 12, 1938, Serial No. 81,034

Term of patent 7 years

To all whom it may concern:

Be it known that I, John G. Francis, a citizen of the United States, residing at Chicago, Cook County, Illinois, have invented a new, original, and ornamental Design for a Glass Teakettle, of which the following is a specification, reference being had to the accompanying drawing forming part thereof.

In the drawing:

teakettle, showing my new design, the spout cover being shown detached from the spout; and

I claim:

The ornamental design for a glass teakettle, as shown.

JOHN G. FRANCIS.
